UNITED STATES PATENT OFFICE.

ROBERT A. REED, OF BROOKLYN, NEW YORK.

IRON MARINE VESSEL.

SPECIFICATION forming part of Letters Patent No. 349,857, dated September 28, 1886.

Application filed March 3, 1885. Serial No. 157,613. (No model.)

To all whom it may concern:

Be it known that I, ROBERT A. REED, of Brooklyn, in the county of Kings and State of New York, have invented a new and useful 5 Improvement in the construction of Iron Marine Vessels, of which the following is a specification, reference being had to the annexed drawings, forming a part hereof.

The object of the invention is to prevent 10 water from leaking into the vessel through any break in the sleeve of the shaft of the propelling-screw.

Figure 1 represents an end elevation of a portion of the stern of an iron vessel, showing 15 the application of the invention thereto; and Fig. 2 is a longitudinal section on the line *y y*, Fig. 1.

Referring to the accompanying drawings by letter, A, Fig. 1, designates the keel of the 20 vessel with the hull rising therefrom, and shown in dotted lines.

D is the shaft of the propeller-wheel, and C is the sleeve thereof. The sleeve has at its outer end the journal-box E for the shaft to 25 turn in, and at its inner end the stuffing-box *d* to prevent water penetrating inward between the shaft and the sleeve.

F is a casing, preferably of metal, surrounding the sleeve, and having its ends *f f'* closely 30 fitting and firmly secured upon the journal-box E and stuffing-box *d*, respectively. The

casing is preferably of the shape shown in the drawings, there being considerable space, *c*, between it and the sleeve.

Should the shaft break within the sleeve, 35 as sometimes occurs, and its broken end fracture the sleeve, the water which enters the sleeve and escapes through said fracture would be prevented from penetrating within the hull of the vessel by the casing F. 40

The object of the space *c* between the sleeve and the casing is to remove the liability of the end of the broken shaft from also breaking the casing and causing the vessel to leak.

Having thus fully described my invention, 45 what I claim is—

In an iron marine vessel, the combination, with the propeller-shaft and the sleeve thereof of having a journal-box at its outer end to accommodate the shaft and a stuffing-box at 50 its inner end to prevent the entrance of water between the shaft and sleeve, of a casing, F, having its outer and inner ends secured water-tight upon the journal-box and the stuffing-box, respectively, and having considerable space between its interior surface and the exterior surface of the shaft-sleeve box, for 55 the purpose specified.

ROBERT A. REED.
